G. M. SPENCER

AIR CLEANING ATTACHMENT FOR AUTOMOBILE CARBURETORS, AIR COMPRESSORS,
AIR BRAKE SYSTEMS, ETC

Filed March 17, 1921

Inventor:
George M. Spencer.
By John C. Higdon
Attorney.

UNITED STATES PATENT OFFICE.

GEORGE M. SPENCER, OF ST. LOUIS, MISSOURI.

AIR-CLEANING ATTACHMENT FOR AUTOMOBILE CARBURETORS, AIR COMPRESSORS,
AIR-BRAKE SYSTEMS, ETC.

Application filed March 17, 1921. Serial No. 453,193.

To all whom it may concern:

Be it known that I, GEORGE M. SPENCER, a citizen of the United States, residing at St. Louis, in the State of Missouri, have invented 55 certain new and useful Improvements in Air-Cleaning Attachments for Automobile Carburetors, Air Compressors, Air-Brake Systems, Etc., of which the following is a specification containing a full, clear, and 10 exact description, reference being had to the accompanying drawings, forming a part hereof.

My invention consists in the novel disclosure hereinafter particularly described 15 and distinctly claimed.

The object of my invention is to provide an improved method of and means for effectually separating dust, dirt, and other heavier-than-air particles from the air that 20 is to be used in automobile carburetors, air-compressors, air-brake systems, and in other situations where the air should be as free as possible of dust, grit, and the like, without restricting the free flow of the air or gas, 25 whether the same be under pressure, at atmospheric pressure, or in a partial vacuum.

A further object of my invention is to provide an improved air-cleaning attachment, which can be applied to the carburetors 30 of automobiles and combustion-engines of all kinds, and to the intake-pipes or outlet-pipes of air-compressors, to the train-pipes of air-brake systems, as well as to other apparatus in which the air or gas should be as 35 free as possible of dust, grit, and other injurious particles that tend to wear out and destroy the efficiency of machinery.

A further object of my invention is to provide an air-cleaning attachment of the 40 class described in the last preceding paragraph, which shall be very simple in construction, operation and repair, highly efficient notwithstanding its simplicity, and of low cost, both as regards its manufacture 45 and attachment to the various lines of machinery upon which it may be used.

In the drawing, the figure is a side-elevation of an air-cleaning attachment, constructed in accordance with my invention, 50 and which may be used in practicing my improved method of separating dust, grit, dirt, and other injurious particles from air or gas.

The numeral 1 designates a straight chamber, that is horizontal and cylindrical in the present illustration, and has a size sufficient to convey the air or gas without undue friction thereof with the internal walls of said chamber.

Said chamber 1 is what I term the primary "momentum-chamber," because in it 60 the air or gas passes in a straight line for a considerable distance, sufficient for it to have a high speed in a straight line; and in case the inlet-pipe 3 is straight for a considerable distance, the said chamber need be but about 65 the length and proportions here shown.

The inlet-end of said momentum-chamber 1 is constructed with an internally-threaded portion 2, or is otherwise provided with a suitable connection by means of which the inlet-pipe 3 may be connected to any well-known automobile carburetor, or to the carburetor of any internal-combustion engine, or to the intake or discharge pipe of any common air-compressor, or to the train-pipe 75 of an air-brake system.

The air or gas enters said momentum-chamber 1 through said inlet-pipe 3, and passes therein in the direction indicated by the arrows, at a high or low speed, depending upon the pressure at which it is being driven; and the sand, grit, dirt, dust or other deleterious particles which are heavier than the air or gas will (by their momentum) 80 pass over and beyond the perpendicular outlet, air passage (or main route passage) 4, and will come into forcible contact with the curved walls of a deflecting-chamber 7, into which the inner end of said first momentum chamber opens; and the curved walls of 85 said chamber 7 will cause the dirt, sand, and other heavier deleterious particles to be deposited in a dirt receptacle 8 at the lower end of said deflecting-chamber, whence said refuse may be easily removed from time to time, by detaching the plug (or other common closing device) 11 from the cleaning opening 10 in the bottom horizontal wall of 90 said receptacle.

Adhesive material, such as greased waste 100 9, may be placed in said receptacle 8, so that the separated dust, sand, and other things will be prevented from rebounding, or returning, to the deflecting-chamber 7.

The air or gas, from which the heavier particles of sand, dust, and the like have been thus separated, passes through said perpendicular passage or chamber 4 into a perpendicular pipe or extension 6, which has its upper end threaded or otherwise connected to the lower end of said chamber 4.

5 A comparatively long horizontal momentum-chamber 19 is connected at one end 10 with a perpendicular momentum and gravity chamber 12, the upper end of which is provided with an internally threaded or other common connection 14, by means of which latter the upper end of said chamber 12 is 15 attached to the lower end of the said perpendicular extension 6 of said perpendicular chamber 4.

Another dirt-receptacle 15 is formed or 20 attached to the lower end of the said perpendicular momentum and gravity chamber 12, so that the combined forces of momentum and gravity will drive forward the fine dirt, dust, and other particles which escaped the first dirt-receptacle 8, and they will be deposited in the second receptacle 15, and from 25 which said refuse may be removed as required, by detaching the cleaning-plug 18 from the cleaning aperture 17 in said receptacle 15.

30 Adhesive material 16, such as common greasy waste or rags, may be placed in said receptacle 15, to prevent rebounding therefrom of the separated dust or other material.

A terminal deflecting-chamber 22, having 35 downwardly-curved walls, is formed upon or attached to the delivery-end of the said long horizontal momentum-chamber 19, so that as the air or gas passes through the latter the remaining fine sand, dirt, and other particles will (by their momentum) pass 40 the air or gas delivery-opening or connection 20 of said horizontal chamber 19 and engage the curved walls of the said deflecting-chamber 22, and be thereby thrown into 45 a final or terminal dirt-receptacle 23, which is formed upon or attached to the lower end of the said terminal deflecting-chamber, and from which dirt-receptacle the refuse material may be easily removed, by detaching 50 the plug 26 from the cleaning-out opening 25 of said dirt-receptacle.

55 Adhesive material, such as greasy waste or rags, may (in some cases) be located in said dirt-receptacle 23, to hold the sand, dust, and other finer particles in said receptacle, and prevent their being drawn upwardly and returned to the air or gas.

Said delivery-connection 20 of the said horizontal momentum-chamber 19 may be 60 attached to the air-intake of a carburetor, or to the intake-manifold of any internal-combustion engine, or to the intake or discharge of an air-compressor, or to the train-pipe or triple-valve of an air-brake system, by a common pipe 21 threaded into or

otherwise connected to said delivery-connection.

The operation.

The operation of my invention will be 70 readily understood from the above description.

However, it may be best to call attention to the fact that my invention provides a free and unobstructed passage for the air 75 and gas throughout its passage through the cleaner.

Nor does the air remix or mingle with the separated particles of dust, dirt, &c., which are at rest in the said dirt-receptacles 8, 15 80 and 23, and cannot rebound therefrom.

The said curved walls of the said deflecting-chambers 7 and 22 impart a centrifugal force to the separated particles, and this assists in separating them from the air current and causing them to be deposited in 85 said dirt-receptacles.

No matter how slight the velocity of the particles of dirt, and dust, or the like, in the said horizontal momentum-chamber 19, 90 they will be carried into the said dirt-receptacle 23, and nothing but perfectly cleaned and clear air or gas, will be delivered through the said delivery or outlet connection 20, and conveyed to the operating 95 machinery or appliances.

I especially call attention to the fact that my apparatus is made up of a series of straight momentum-chambers, each of which terminates in a dirt-receptacle, and 100 that the air and gas to be cleaned is passed consecutively through each momentum-chamber.

The primary, or initial, momentum-chamber 1 may be used separately in some cases, 105 where there is a constant (or almost constant) high velocity of volume of the air or gas under pressure, or under more or less vacuum.

In using the primary momentum-chamber 110 1 alone, the perpendicular outlet 4 thereof would, of course, be connected directly to the intake of the carburetor, air-compressor, or other device; or it could be attached to the discharge-pipe of an air-compressor, or to 115 the train-pipe or triple-valve of an air-brake system; and all of the remaining parts of my apparatus could be omitted in such cases, as the said primary momentum-chamber 1 and its dirt-receptacle 8 will 120 perfectly remove all particles of dust from the air or gas, and will prevent the dirt, &c., from rebounding, and again entering the current of air or gas.

But, in all cases where the air or gas 125 current is of low velocity, the primary momentum-chamber 1 may be omitted, and the remaining parts will perfectly clean the air or gas, the said perpendicular parts 6, and 12, the dirt-receptacle 15, and the long 130

horizontal momentum-chamber 19, with its final dirt-receptacle 23, will by combining gravity, momentum, and centrifugal force, produce an excellent result in this regard.

5 However, to meet all conditions, in actual practice, the entire combination of all the various parts of my apparatus should be used, and the air or gas will be perfectly cleaned, no matter what the velocity, pressure, or vacuum of the air or gas may be.

10 I do not limit myself to the exact size or proportions of the parts of my apparatus shown in the present drawings; nor do I limit myself to the identical details of parts 15 thereof, as it is apparent that any skilled workman can change said parts and proportions without departing from the spirit or scope of my invention.

I claim:—

20 1. An air cleaning attachment for carburetors, air compressors, air brake systems, and the like; comprising a straight horizontally disposed momentum chamber to convey air without undue friction thereof 25 with the internal walls of said chamber; an outlet directed downwardly from said momentum chamber, intermediate its ends, said momentum chamber terminating in a downwardly curved deflecting chamber for massing 30 the heavier particles of dirt and dust against the outer wall thereof, said deflecting chamber terminating in a receptacle of greater diameter than the diameter of said deflecting chamber into which the separated 35 dirt and dust is carried and deposited by its momentum past the said outlet and a removable closure plug for the bottom wall of the enlarged receptacle.

40 2. An air cleaning attachment for carburetors, air compressors, air brake systems, and the like; comprising a straight primary momentum chamber to convey air without undue friction thereof with the internal walls of said chamber; a downwardly 45 directed air outlet for said chamber; said straight primary momentum chamber terminating at one end in a downwardly curved deflecting chamber of the same diameter as said straight primary momentum chamber for massing the dirt and dust against the outer wall thereof in its passage therethrough; a receptacle of greater diameter than said deflecting chamber forming a termination of said deflecting chamber into 50 which the heavier particles of dirt and dust are carried and deposited by their momentum past said outlet; and a series of additional separating chambers with diameters the same as said primary momentum chamber having communication with said outlet and terminating in additional receptacles of greater diameter than said additional separating chambers and for further cleaning the air which is discharged from the outlet 55 of said primary momentum chamber into

which the finer particles of separated dirt and dust are carried and deposited by their momentum through said additional separating chambers.

60 3. An air cleaning attachment for carburetors, air compressors, air brake systems, and the like; comprising a primary straight horizontally disposed parallel walled momentum chamber terminating at one end in a downwardly curved deflecting chamber; an enlarged dirt receptacle formed at the terminal end of said deflecting chamber; a removable closure plug for the bottom wall of said enlarged dirt receptacle, a perpendicular chamber into which the partially cleaned air is discharged downwardly from said primary momentum chamber intermediate its ends; an enlarged dirt receptacle 65 formed at the terminal end of said perpendicular chamber; a laterally directed discharge connection for said perpendicular chamber arranged above the enlarged dirt receptacle thereof, and a removable closure plug for the bottom wall of said last mentioned enlarged dirt receptacle.

70 4. An air and gas cleaning attachment for the purposes described; comprising a series of straight horizontal parallel walled momentum chambers which terminate in deflecting chambers having curved walls; an enlarged dirt receptacle forming the closed 75 end of each of said deflecting chambers; inlets and outlets for said series of connected momentum chambers; and a perpendicular chamber for connecting the outlet of an adjacent momentum chamber with the inlet of another one of said momentum chambers.

80 5. An air and gas cleaning attachment for the purposes described; comprising a series of suitably spaced straight horizontally disposed momentum chambers; deflecting chambers at the terminal end of each of said momentum chambers; an enlarged dirt receptacle at the terminal end of each of said deflecting chambers; a perpendicular chamber connecting the discharge end of the upper horizontal momentum chamber with the inlet end of a lower horizontal momentum chamber; clean out closures for each of said enlarged dirt receptacles, whereby the latter may be opened and cleaned out; and attachment parts for the primary and final horizontal momentum chambers.

85 6. An elastic fluid cleaning attachment of the class described; comprising a primary straight horizontal momentum chamber to convey an elastic fluid without undue friction thereof with the internal walls of said chamber, said momentum chamber curving downwardly at one end to form a deflecting chamber; an enlarged dirt receptacle forming the terminal end of said deflecting chamber; a downwardly directed outlet for said momentum chamber; a perpendicular chamber communicating with said down-

wardly directed outlet; an enlarged dirt receptacle forming the lower end of said perpendicular chamber; a second straight horizontal momentum chamber having communication with the perpendicular chamber at a point near its lower end; said second horizontal momentum chamber terminating in a downwardly curved deflecting chamber; an enlarged dirt receptacle forming the terminal end of said deflecting chamber; said second straight horizontal momentum chamber having an upwardly directed outlet; and a

removable clean out plug for each of the aforesaid dirt receptacles, whereby the receptacles may be opened and the accumulated foreign particles separated from the elastic fluid removed. 15

In testimony whereof, I have signed my name to this specification in presence of two subscribing witnesses.

GEORGE M. SPENCER.
